UNITED STATES PATENT OFFICE.

HERBERT S. ATKINSON, OF EAST ORANGE, NEW JERSEY, ASSIGNOR TO THE HAYWARD COMPANY, OF NEW YORK, N. Y., A CORPORATION OF NEW YORK.

BUCKET.

1,311,259.

Specification of Letters Patent. Patented July 29, 1919.

Application filed May 26, 1915. Serial No. 30,521.

To all whom it may concern:

Be it known that I, HERBERT S. ATKINSON, a citizen of the United States, and residing at East Orange, in the county of 5 Essex and State of New Jersey, have invented certain new and useful Improvements in Buckets, of which the following is a full, clear, and exact specification, such as will enable others skilled in the art to which it 10 appertains to make and use the same.

This invention relates to an improvement in excavating buckets, and while I have shown the same as applied to sheave-operated buckets of the clam-shell type, I do not 15 wish to be understood as limiting my invention to the precise form of bucket illustrated. I may say, however, that it has especial utility in those forms of bucket where in the bowl sections have pivotal connection 20 through connecting rods or otherwise, with the supporting head. With such constructions there is always more or less danger, when the bucket is lowered on to the material, if the material forms an uneven surface, 25 of the bucket tilting and the head and upper portions of the connecting rods being thrown out of their normal relative positions.

The object of my invention is to provide 30 means movably connected to both the bucket-head and the connecting rods, whereby the relative movement of the connecting rods and head is controlled within certain definite limits, as well during the normal operation of the bucket upon a substantially even surface, as when operated upon a more or less uneven bed of material. The bucket-head is thereby not only prevented from 35 tilting, being retained always in its normal operative position, but the connecting rods themselves, in operation, are caused to move substantially coincidently with each other, which also is desirable.

Another object of my invention is to provide 40 means, for the purpose stated, which shall not interfere with the normal operative movement of the bucket parts, which is economical to manufacture and install in the bucket, and when installed, is so positioned as to be protected against hard usage, 45 is itself strong and durable, and gives an additional feature of strength and durability to the bucket as a whole, since it forms a dependable safe-guard against possible 50 accident due to tilting of the bucket-head.

which may cause it to topple over in distorted position.

These objects will be readily apparent from the following specification, taken in connection with the accompanying drawings 60 in which,

Figure 1 is a side elevation of a bucket embodying my control device;

Fig. 2 is a plan view, in part broken away;

Fig. 3 is an enlarged detail, with certain parts removed; and

Fig. 4 is an end view.

Referring to the construction illustrated, A, indicates, in whole, a clam-shell bucket, 70 comprising a supporting head indicated in whole at B, a plurality of bowl sections indicated at C, D, which are pivotally connected to the links E, the latter being in turn pivotally connected to the head B. 75

The bucket illustrated is of the sheave-operated type, being provided with a plurality of sheaves in the weighted member F in the lower center and a plurality of sheaves in the upper center, or head B of 80 the bucket. A closing line H passes through a rope thimble H', downwardly and around one of the outside sheaves in the lower center, upwardly and over the alining outer sheave in the upper center, thence downwardly and around the middle sheave in the lower center, thence upwardly and around the opposite outer sheave in the upper center, thence downwardly and around the other outer sheave in the lower center, and 85 upwardly and through the other rope thimble H''. Around the central sheave in the upper center passes a holding rope H³, for supporting the bucket. The bucket is opened by slackening off the closing line H, 90 while holding taut the holding line, whereupon the weight F descends, opening the bowl sections. It is closed by hauling in on the closing rope H, drawing the upper and lower centers together. 95

To the foregoing described features *per se* I make no claim of invention as it is in general, now a well-known form of bucket.

As before stated, my invention, has to do more especially with the means for retaining the bucket-head and connecting rods in their normal relative positions, which I will now proceed to describe.

The supporting head B comprises a casting, formed centrally with a sheave casing 110

indicated at I, from which project on opposite sides thereof and angularly thereto, a plurality of bosses J, J', J², J³, to which are secured, by means of the pins K, the respective connecting rods E.

Also formed as a part of the supporting head B, at each side thereof, and preferably integral with the bosses J, J', J², J³, is an intermediate boss L.

- 10 Movably secured to the upper ends of the adjoining pairs of connecting rods E, at each side of the supporting head, is a guide plate M. This plate is of substantially inverted T-shape, the two lower legs of which 15 M', M², project horizontally outwardly and are respectively provided with a slot M³, horizontally elongated, through which respective slots is passed a bolt N movably securing the legs M', M², to the respective 20 upper ends of the connecting rods E at the inner sides thereof. At the upper end of the middle leg O, and also at the lower intermediate portion of the plate are provided respectively a plurality of slots O³, which 25 are vertically elongated, and through which, and into the boss L, are passed screw bolts P, movably securing the plate, at the points mentioned to the boss L of the supporting head B. It will be understood that in the 30 normal operation of the bucket, when the bowl sections open and close, by means of the lowering and raising of the weight F in the lower center, the connecting rods E have a limited oscillating movement, from the 35 pivotal connections at the bucket head, and the oscillations are relatively slight as compared with the length of movement at the lower ends of the connecting rods; therefore the vertical and horizontal slots in the guide 40 plate M are not required to be of any considerable extent. It will be understood that the shanks of the bolts securing together the upper ends of adjoining pairs of connecting rods and the lower legs of the guide plate 45 are loosely mounted in the slots of the guide plate, likewise the screw bolts securing the guide plate to the supporting-head. By referring to Fig. 3 the operation of the guide plate will be made clear, in which figure is 50 illustrated, in full lines, how the connecting rods, on the opening of the bucket, have described a small arc of a circle in their oscillating movement, the bolts N being carried to the outer end of the respective slots M³, 55 and in this arcing movement raising the guide plate, so that the bolts P rest in the lowermost portion of the respective slots O³.

When the bucket is closing the connecting rods oscillate to the position indicated in 60 dotted lines in said Fig. 3, during which movement the guide plate will be lowered in position, and the respective bolts will occupy positions in the respective slots at the ends opposite to those the bolts are illustrated as 65 occupying in said figure.

While I have described the construction and operation of but one of these guide plates, it will be understood that two will be employed, one at each side of the supporting head, as indicated in Fig. 2 of the 70 drawings.

It will be apparent that my guide plates control, within definite limits, the relative movements of adjoining pairs of connecting rods, and the movement relative thereto of 75 the bucket head, causing adjoining pairs of connecting rods to move coincidently with each other, and also effectively preventing the tilting or abnormal movement of the bucket-head.

I desire it to be understood that I do not confine myself to the precise details of construction and arrangement of the invention herein set forth, as modifications and variations may be made without departing from 85 the spirit of the invention, as defined by the appended claims.

What I claim is:

1. In an excavating bucket, the combination with a plurality of oscillating connecting rods, and a supporting head, to which said connecting rods are pivotally connected, of a guide plate having a vertically slotted portion movably affixed to the bucket-head and other portions horizontally slotted mov- 90 ably secured to an adjoining pair of connecting rods, whereby the relative movements of the connecting rods and supporting head are limited and controlled, said guide plate having no part in supporting said 100 connecting rods or head.

2. In an excavating bucket, the combination with a plurality of oscillating connecting rods, and a supporting head, said head including at each side thereof, a plurality of spaced-apart bosses to which said connecting rods are pivotally connected, of a guide plate having a vertically slotted central portion movably affixed to the bucket-head between said bosses, and a horizontally slotted portion at each lower end thereof movably secured to an adjoining pair of connecting rods.

3. In an excavating bucket, the combination with a plurality of oscillating connecting rods and a supporting head to which said rods are pivotally connected, of means for controlling and limiting the relative movement of the head and connecting rods, said means comprising a plate having a plurality of vertical slots, and a plurality of horizontal slots and fastening means projecting through the first-named slots whereby the plate is movably connected to the bucket-head, and fastening means projecting 115 through the second named slots whereby said plate is movably connected to an adjoining pair of connecting rods.

4. In an excavating bucket, the combination with a plurality of oscillating connect- 130

ing rods and a supporting head to which said rods are pivotally connected, of means for controlling and limiting the relative movement of the head and connecting rods, 5 said means comprising a pair of control plates adapted to fit operatively between adjoining pairs of connecting rods and the bucket head, each plate having a plurality of vertical slots and fastening means whereby the plate is movably connected to the bucket-head, and a plurality of horizontal slots and fastening means whereby the plate is movably connected to adjoining pairs of connecting rods.

15 5. In an excavating bucket, the combination with a plurality of oscillating connecting rods and a supporting head to which said rods are pivotally connected, of a control member for limiting the relative movement of the head and connecting rods, comprising a plate adapted to fit operatively in perpendicular position between the connecting rods and the bucket head, and having a plurality of vertical slots and a plurality 25 of horizontal slots, fastening members extending respectively through said vertical slots and movably connecting the plate to the bucket-head, and fastening members extending respectively through said horizontal slots and movably connecting said plate to adjoining pairs of connecting rods.

20 6. In an excavating bucket, the combination with a plurality of oscillating connecting rods and a supporting head to which said rods are pivotally connected, of a guide plate positioned adjacent the pivotal connection of said rods with said head, means connecting said guide plate to the supporting head with freedom for movement relative to the latter, and means connecting said plate to an adjoining pair of connecting rods movably relative thereto, whereby said guide plate limits and controls the relative movements of the connecting rods and 45 bucket head, said guide plate having no part in supporting said connecting rods or head.

40 7. In an excavating bucket, the combination with a plurality of oscillating connecting rods and a supporting bucket head to which said rods are pivotally connected, of a control member for said head and rods, comprising a guide plate having portions vertically and horizontally slotted, fastening 55 members for securing said guide plate, through the vertically slotted portion to

the bucket head, and fastening members securing said guide plate, through the horizontally slotted portion to an adjoining pair of connecting rods, near the pivotal connection of said rods with said head, whereby the movement of the head and connecting rods relatively to each other is limited and controlled.

60 8. In an excavating bucket, the combination with a plurality of oscillating connecting rods and a supporting bucket head to which said rods are pivotally connected, of means for controlling and limiting the relative movement of the head and connecting rods, said means comprising a plate having a vertically slotted portion and a horizontally slotted portion, means movably securing the vertically slotted portion to the bucket head, and means movably securing the horizontally slotted portion to an adjoining pair of connecting rods, near the pivotal connection of said rods with said head.

65 9. In an excavating bucket, the combination with a plurality of oscillating connecting rods and a supporting bucket head to which said rods are pivotally connected, of means for controlling and limiting the relative movement of the head and connecting rods, said means comprising a plate adapted to fit operatively between the connecting rods and the bucket-head, said plate being perforated, and means extending through the perforations movably connecting the plate to the bucket-head and to an adjoining pair of connecting rods.

70 10. In an excavating bucket, the combination with a plurality of oscillating connecting rods and a supporting bucket-head to 95 which said rods are pivotally connected, of a control member for said head and rods, comprising a plate adapted to fit operatively between the connecting rods and the bucket-head, said plate having a plurality of arm-like extremities, certain of said extremities being horizontally slotted, and pinned through said slots, movable relatively, to an adjoining pair of connecting rods, and a portion of said plate intermediate said 100 extremities being vertically slotted, and pinned through the vertical slots, movable relatively, to the bucket-head.
